UNITED STATES PATENT OFFICE

157,926

SEWING-MACHINE CABINET

Julian U. von der Lancken, Flushing, N. Y., assignor to The Singer Manufacturing Company, Elizabeth, N. J., a corporation of New Jersey

Application April 9, 1948, Serial No. 145,617

Term of patent 14 years

(Cl. D33—19)

To all whom it may concern:

Be it known that I, Julian U. von der Lancken, a citizen of the United States, residing at Flushing, in the county of Queens and State of New York, have invented a new, original, and ornamental Design for Sewing Machine Cabinets, of which the following is a specification, reference being had to the accompanying drawing, forming a part thereof.

Fig. 1 is a front perspective view of a sewing machine cabinet showing my new design.

Fig. 2 is a fragmental sectional view taken on the line 2—2 of Fig. 1.

Fig. 3 is a sectional view taken on the line 3—3 of Fig. 1.

The top of the cabinet is rectangular and the sides not shown are substantially the same as those illustrated, except that the rear panel and the rear of the legs are plain.

I claim:

The ornamental design for a sewing machine cabinet, substantially as shown and described.

JULIAN U. VON DER LANCKEN.
